ATTORNEY

UNITED STATES PATENT OFFICE.

JOHN NIXON, OF FARMLAND, INDIANA.

DEPURATOR.

SPECIFICATION forming part of Letters Patent No. 478,548, dated June 7, 1892.

Application filed December 4, 1891. Serial No. 413,936. (No model.)

To all whom it may concern:

Be it known that I, JOHN NIXON, a citizen of the United States, residing at Farmland, in the county of Randolph and State of Indiana, have invented a new and useful Improvement in Medicated-Vapor Apparatus, of which the following is a specification.

My invention relates to an improved apparatus for administering medicated vapor for the cure of lung and throat diseases.

The object of my improvement is to provide for the treatment of lung and throat diseases an apparatus by the means of which the patient may be surrounded with and compelled to breath a medicated atmosphere, the quality and pressure of which may be under the control of the operator.

The accompanying drawings illustrate my invention.

Figure 1 represents a front elevation of the apparatus. Fig. 2 represents a vertical section of the vapor-chamber. Fig. 3 represents a vertical section of the vapor-generator and its connections.

In the drawings, A represents an inclosed structure forming the vapor-chamber and having one open side for the entrance of the patient, which open side is closed by a removable door (not shown) during the treatment, so as to form a practically air-tight room, in which the patient is inclosed. Arranged a short distance below the top of chamber A is a horizontal partition B. Resting upon partition B and projecting through the top of chamber A is a metallic vessel C, which is filled with prepared wool D or like absorbent material, the purpose being to hold a liquid medicine in such form as to be conveniently vaporized. Extending from vessel C in the

space between partition B and the top of the chamber are a series of pipes E, which project through partition B and downward along the interior sides of the chamber, said projecting pipes being perforated, so as to discharge into the chamber. The open lower ends of pipes E on each side respectively enter a drip-pipe F, by means of which any fluids formed therein may be collected in cups G G. Arranged at one side of chamber A is a boiler H, the upper part of which is connected with vessel C by means of the steam-pipe I, which is provided with a stop-

valve J and a drip-cock L. Arranged on opposite sides of boiler H are a pair of reservoirs M and N. Each reservoir is connected at the bottom with the interior of the boiler by a pipe O and is connected at the top with the steam-pipe I by a pipe P, all of said pipes being provided with suitable stop-valves.

Connected with chamber A by a pipe R is an air-pump S, by means of which the air in chamber A, when the chamber is closed, may be attenuated to any desired degree.

The operation of my apparatus is as follows: Preparatory to placing the patient in the chamber A boiler H is partly filled with water, reservoirs M and N are filled, respectively, with different medicines, in a liquid form, which it is desired to administer either jointly or separately, and the absorbent filling of vessel C is likewise saturated with liquid medicine. Medicine is now admitted to the boiler from one or both of reservoirs M and N until the water in the boiler has been medicated to the desired degree. Heat being applied to the boiler, the medicated water therein is vaporized until a slight pressure has been attained. The patient is now placed in chamber A and the chamber closed. By means of the air-pump the air is partly exhausted from chamber A, thus compelling the patient to breathe deeply. Valve J is now opened and the vapor from boiler H passes to vessel C, where it is still further charged with medicine, and then passes through pipes E to the interior of chamber A, where it is distributed through the perforations in the sides of pipes E. An artificial atmosphere is thus created which penetrates to the farthest recesses of the lungs and applies the medicines directly to the diseased surfaces.

By means of the reservoirs M and N, the boiler, and chamber A a great variety of combinations of medicines may be used, according to the varying conditions of the patient.

I claim as my invention—

1. In a medicated-vapor apparatus, the combination of the closed chamber, the vessel mounted in the top of said chamber and provided with an absorbent filling, the steam-supply pipe connected with said vessel, the distributing-pipes extending from said vessel beneath the top and along the sides of said chamber, and the drip-pipe arranged to re-

ceive the ends of said distributing-pipes, all arranged to co-operate substantially as set forth.

2. In a medicated-vaporapparatus, the combination of the closed chamber, the boiler, the steam - pipe connecting said chamber and boiler, the pair of reservoirs arranged adjacent to said boiler, suitable pipes connecting the lower ends of the reservoirs with the interior of the boiler, pipes connecting the upper ends of the reservoirs with said steam-pipe, and suitable stop-valves arranged in said pipes between the reservoirs and the boiler and between the reservoirs and the steam-pipe, all arranged to co-operate substantially as and for the purpose set forth.

3. In a medicated-vapor apparatus, the combination of the closed chamber, the air-pump connected therewith, the vessel mounted in the top of the chamber, provided with an absorbent filling and connected with the interior of the chamber by a series of distributing-pipes, the steam-pipe connecting the boiler and said vessel, the boiler, and the medicine - reservoirs connected with said boiler, all arranged to co-operate substantially as and for the purpose set forth.

JOHN NIXON.
